UNITED STATES PATENT OFFICE.

JOHN THOMSON, OF BROOKLYN, NEW YORK, ASSIGNOR TO JOHN THOMSON PRESS COMPANY, OF NEW YORK, N. Y., A CORPORATION OF NEW JERSEY.

DEVICE FOR IMPARTING COMBINED ROTARY AND RECIPROCATING MOTION.

SPECIFICATION forming part of Letters Patent No. 762,958, dated June 21, 1904.

Application filed October 23, 1902. Serial No. 128,469. (No model.)

To all whom it may concern:

Be it known that I, JOHN THOMSON, a citizen of the United States, residing at Brooklyn, in the county of Kings and State of New York, have invented certain new and useful Improvements in Devices for Imparting Combined Rotary and Reciprocating Motion, of which the following is a specification.

The invention is an improvement in the device for imparting combined rotary and reciprocating motion illustrated in my patent of February 21, 1888, No. 378,344; and the object hereof is to render effective a modification referred to in this patent.

Having reference to the aforesaid patent, the statement is therein made that two epicyclic gears may be used instead of one; but it was not then comprehended that this could not be realized in practice by a mere duplication of structure. As a matter of fact, I have but recently ascertained that to accomplish the use of a pair of epicyclic gears for coöperatively effecting the reciprocating action requires quite a different construction. This is the subject of the present application.

In the drawings, Figure 1 is a detail in longitudinal center section and elevation denoting an embodiment of the invention. Fig. 2 is an end view; and Fig. 3 is a transverse section on the line B of Fig. 1, in which the gears are revolved half of a turn.

The operation of this device will be briefly described in so far as relates to the present improvement. The object sought is to cause the cylinder 7 to revolve with the shaft 21 and also to slide back and forth thereon. Its principal application in practice is in connection with platen printing-presses, where such devices are usually termed "changers," being used for distributing the ink upon the form-inking and the distributor rollers. Assuming that the present drawings had but one epicyclic gear, as 12, the device would then be a duplication of that illustrated and described in the aforesaid patent, No. 378,344. The shaft-fixture 16 is secured, as by the set bolt 23, to the shaft 21, and upon the stud 14 is mounted the gear 12, free to revolve thereon.

Upon the upper side of the gear 12 is a crank-stud 19, whose throw or eccentricity is denoted by the lines 27 29. The gear 12 meshes with the gear 24, which is made fast to the frame 25 of the machine and is prevented from rotating, as by the bolt or bolts 26. The crank-stud freely engages a slot 5, formed within the cylinder. Now upon imparting revolution to the cylinder and also to the shaft this will cause the epicyclic gear 12 both to rotate around the gear 24 and also to revolve upon its stud or bearing 14. Consequently the crank-stud will reciprocate the cylinder upon the shaft back and forth for each full revolution of the gear 12. As bearing upon the present matter, the following extract is quoted from the specification of the aforesaid patent, No. 378,344: "When severe duty is required, another stud may be formed and an additional gear may be mounted thereon the duplicate of gear 25, the cylinder also having another slot diametrically opposite from that shown in the drawings. In other words, the cylinder would then be reciprocated by a pair of gears, and so arranged the action would be in its theoretically most perfect form."

To assemble the single epicyclic gear with in the cylinder as shown in Patent No. 378,344, it is first inserted into the cylinder out of its center and then carried outwardly until its actuating-stud engages the slot, after which the shaft is inserted, thus securing the parts in place. Obviously this cannot be done when two gears are used each mounted oppositely from the other, nor can they be revolved into place without such an excess of room and sacrifice of mechanical effectiveness as would not be permissible in the class of structures to which the device is chiefly applicable—namely, the inking-cylinders of platen printing-presses. To obviate this difficulty, I form the slots 5 5^a with their inner walls 6 6^a as a part of the cylinder 7; but the outer walls 8 9 are made from separate pieces inserted in and detachably secured to the inner perimeter 10 of the cylinder, as by means of the screws or studs 11. In this wise the epicyclic gears 12 13 are mounted upon the studs 14 15 of the

shaft-fixture 16, and the friction blocks or rollers 17 18 are applied to the crank-studs 19 20, and all as a self-contained structure is concentrically inserted, after which the outer wall pieces 8 9 are secured to their seats. Finally, the driving-shaft 21 is slid through the bearing 22 of the fixture, secured thereto as by the set-bolt 23, and the fixed or driving gear 24 is applied over the end of the shaft to engage the epicyclic gears, being secured to the frame of the machine, as 25, by the bolt or bolts 26.

In constructing and assembling this device it is essential to observe that the centers of the 15 crank-studs, as 27 28, are respectively to the right and left of the center, as 29, of the shaft-fixture, also that both crank-studs must lie in the same line with respect to the teeth of the gears and that when an uneven number of 20 teeth are employed in the epicyclic gears—say as thirty-five—then an even number of teeth must be in the fixed driver—say as ten.

The advantages of this arrangement and construction are that the area of the bearing-surfaces is doubled and that no cramping thrusts 25 are transmitted to the shaft or to the cylinder, hence greatly increasing the endurance and effectiveness of the device.

I claim—

The combination with the fixed gear, the 30 epicyclic gears, the crank-studs, the shaft-fixture and the shaft, of a cylinder having the outer walls of the slots which engage the crank-studs detachably secured to the said cylinder, substantially as and for the purpose set 35 forth.

In testimony whereof I have signed my name to this specification in the presence of two subscribing witnesses.

JOHN THOMSON.
